(57) **CLAIM**

The ornamental design for a frame for an output collection system of a large format printer, as shown and described.

DESCRIPTION

FIG. 1 is a left, front perspective view of a frame for an output collection system of a large format printer is shown in a deployed position.

FIG. 2 is a right, front perspective view of the frame of FIG. 1.

FIG. 3 is a front view of the frame of FIG. 1.

FIG. 4 is a left side view of the frame of FIG. 1.

FIG. 5 is a right side view of the frame of FIG. 1; and,

FIG. 6 is a top view of the frame of FIG. 1.

The rear view and the bottom view of the frame of FIG. 1 form no part of the claimed design.

The features shown in broken lines form no part of the claimed design.

1 Claim, 6 Drawing Sheets
